RADIO COMMUNICATION SYSTEM

Harold O. Peterson, Riverhead, N. Y., assignor to
 Radio Corporation of America, a corporation
 of Delaware

Application January 16, 1941, Serial No. 374,682

3 Claims.

(Cl. 250—6)

The present invention relates to radio transmitting and receiving systems and, more particularly, to the physical arrangement of the plant structure associated therewith.

An object of the present invention is the arrangement of the operating plant structure of a radio communication station with a minimum economy of space.

Still another object is the arrangement, as aforesaid, so that the transmitted energy from the transmitting antennas will not be picked up by the receiving antennas.

A further object of the present invention is the prevention of interaction between closely adjacent receiving and transmitting structures.

Still another object of the present invention is to take full advantage of the directive properties of transmitting and receiving antenna structures.

In accordance with the principles of my invention I propose to provide receiving and transmitting apparatus within a single operating building, to provide adequately shielded transmitter and receiver structures and transmission lines and to separate the receiving and transmitting antennas as far as practicable within the confines of the available space and to so orient the transmitting and receiving antennas as to take best advantage of their directive characteristics.

Since transmitting and receiving directive antennas generally have very little radiation or response for directions over a rather broad angle centered around the directions at right angles to the direction for which the antennas were designed, I propose to so locate the transmitting and receiving antennas that such antenna is located within the area of minimum radiation or response of the other of the antennas.

Furthermore, I propose to so orient the beam of each of the receiving and transmitting antennas that it does not cross the operating building or any of the other antennas.

The present invention will be more clearly understood by reference to the following detailed description which is accompanied by drawings in which Figure 1 shows one arrangement of real estate for a requirement of transmitting and receiving over a single direction without interaction between the antennas; Figure 2 shows a similar arrangement to that shown in Figure 1 but modified so as to be suitable for operation over a number of different directions within an arc of 90 degrees; Figure 3 shows a further development of the present invention in which greater arc of

operation is completely covered than in the case of Figure 2, while Figure 4 shows diagrammatically the arrangement of the transmitting and receiving structures within the operating building so as to obtain minimum interaction between transmitter and receiver.

Figure 1 shows a most economical arrangement of real estate for requirement of transmitting and receiving over a single direction circuit. A substantially square tract of land, 10, has located thereon a transmitting antenna TA and a similar tract 11 has located thereon the receiving antenna structure RA. For most purposes it will be sufficient if each of these tracts has an area of approximately 40 acres since all of the land between tracts 10 and 11 is not needed. Between the two tracts 10 and 11 is located a small tract 12 for the operating building OB. Rights-of-way 13 and 14 are provided connecting tract 12 with tracts 10 and 11 for running the transmission lines TLT and TLR. The arrangement shown in Figure 1 may be considered, for the purpose of illustration, as being designed to transmit and receive in a southerly direction. Ordinarily, it will, therefore, be desirable to place the antennas and, particularly, antenna RA as near the north end of the tract as possible so that interference from radiating sources outside of the tract will be reduced as much as possible.

The arrangement shown in Figure 2 is somewhat similar to that shown in Figure 1, except that it is laid out on a single rectangular tract of ground approximately one quarter of a mile wide and three quarters of a mile long. The structure shown in this figure is designed to operate over a number of different directions covering an arc of approximately 90 degrees, for example, one transmitting antenna TA₁ may be considered as directed in a general southerly direction while another transmitting antenna TA₂ may be considered to be directed in a general easterly direction. By using one or the other of these transmitting antennas alone, or both in combination, it is possible to operate in any given direction between due east and due south. The two transmitting antennas are connected to the operating building OB by means of transmission lines TLT₁ and TLT₂. At the end of the plot remote from the transmitting antennas are located receiving antennas RA₁ and RA₂. The receiving antenna RA₁ is directed in the same general direction as the transmitting antenna TA₁ and the other receiving antenna RA₂ is directed in the same direction as transmitting antenna TA₂. By a choice of the receiving antennas, or a combination

thereof, as described with reference to the transmitting antennas, any given direction between the east and south may be covered thereby. The two receiving antennas are connected to the operating building by transmission lines TLR₁ and TLR₂. It will be noted in this figure that the receiving and transmitting antennas are so located that their zones of maximum effectiveness do not lie across any other antennas or across the operating building OB. In this manner interference between the receivers and transmitters is reduced to a minimum.

In Figure 3 I have shown a further development of the structure shown in Figure 2. In this embodiment the plant structure is disposed over a tract of land 31 which is preferably square in shape and may have a total area of approximately 160 acres. However, since the northwest corner is not used, nor do the beams from any of the antennas cross this corner, it need not be reserved for the station. The receiving antennas, RAS and RAE, are paired with the transmitting antennas, TAE and TAS, to provide duplex operation in several directions at once. The operating building OB is, as in the previous embodiments described, located approximately midway between the transmitting and receiving antennas. Transmission lines TLT and TLR connect the antennas to the equipment within the operating building OB. In this arrangement eastward transmission is radiated by the antennas, TAE, and transmission toward the south is from antennas TAS. I have indicated in this figure angles α and β over which minimum energy is radiated from the transmitting antennas TAE and TAS. It should be noted that the receiving antennas RAS and RAE are situated within the area of minimum energy from the transmitting antennas. Furthermore, the receiving antennas do not point toward the transmitting antennas or the operating building OB, nor does the transmitted energy from the antennas TAE and TAS cross the operating building OB.

In Figure 4 I have shown a preferred manner of arranging the equipment within the operating building OB. The building is preferably constructed of some conductive material so as to obtain as much shielding effect as possible. Within the building OB is arranged a shielded room 42 within which is located transmitter 43. The energy generated by transmitter 43 is carried to the transmitting antennas by transmission line TLT which is preferably of the concentric cable type so as to reduce unwanted radiation as much as possible. Balanced two wire lines may, of course, be used if desired. In order to prevent interference due to energy traveling back on the power line from the transmitter a low pass filter LPF is placed in series with the power line at the point where the power line passes through the

shielding wall 42. The receivers 44 within the main building OB are placed in any convenient location therein and connected to the receiving antennas by a concentric transmission line TLR.

5 While I have particularly shown and described several modifications of my invention, it is to be distinctly understood that my invention is not limited thereto but that improvements within the scope of the invention may be made.

I claim:

1. A radio communication station comprising a system of directive transmitting antennae, a system of fixed directive receiving antennae spaced therefrom, said systems being arranged to have substantially non-overlapping zones of maximum effectiveness in different directions, each zone being effective over an angle not exceeding 90 degrees, transducer equipment located between said systems, transmission lines connecting said systems to said transducer equipment, said antennae being so disposed that within said angle the zone of effectiveness of each of said systems does not cross the other of said systems, nor cross the transducer equipment nor the transmission lines connecting the other system to said transducer equipment, said transducer equipment and said transmission lines being located in a zone of minimum radiation from said transmitting antenna.

2. A radio communication station comprising a fixed directive transmitting antenna, a fixed directive receiving antenna spaced therefrom, said antennae being arranged to have their zones of maximum effectiveness cover substantially non-overlapping angles not exceeding 90 degrees, transducer equipment located substantially midway between said antennae and connected to said antennae, said antennae being so disposed that within said angle the zone of effectiveness of each of said antennae does not cross the other of said systems nor the transducer equipment connected thereto, said transducer equipment being located in a zone of minimum energy radiation from said transmitting antennae.

3. A radio communication station comprising fixed directive transmitting and receiving antennas arranged at opposite ends of a tract of land and an operating building housing transducer equipment for said antennas and arranged substantially at the center of said tract, said antennas being so arranged so as to have substantially non-overlapping zones of maximum effectiveness each zone covering an angle not exceeding 90 degrees, the zone of each of said antennas being such that it does not cross the other antenna or said operating building, said receiving antenna being further so arranged as to have a maximum amount of unoccupied area of said tract within its zone of maximum effectiveness.

HAROLD O. PETERSON.
